Silas Jacques Guillon, Champlain, N. Y., assignor of one-half to Alexis D. Andreef, Champlain, N. Y.

Application October 11, 1952, Serial No. 21,808

Term of patent 14 years

(CL. D15—8)

To all whom it may concern:

Be it known that I, Silas Jacques Guillon, a citizen of Canada, residing at Champlain, county of Clinton, State of New York, have invented a new, original, and ornamental Design for a Chair, of which the following is a specification, reference being had to the accompanying drawing, forming a part thereof.

The single figure is a perspective view of a chair, showing my new design.

I claim:

The ornamental design for a chair, as shown.
SILAS JACQUES GUILLON.
